UNITED STATES PATENT OFFICE.

VICTOR CHARTENER, OF PITTSBURGH, PENNSYLVANIA.

ROLLING-MILL FOR METAL SHEETS AND STRIPS.

1,127,591.

Specification of Letters Patent.

Patented Feb. 9, 1915.

Application filed June 27, 1913. Serial No. 778,084.

To all whom it may concern:

Be it known that I, VICTOR CHARTENER, a citizen of the United States, residing at Pittsburgh, in the county of Allegheny and State of Pennsylvania, have invented new and useful Improvements in Rolling-Mills for Metal Sheets and Strips, of which the following is a specification.

My invention relates to rolling mills for metal sheets and strips. Hot rolled strip metal varies in width from twenty inches and over down to one and a half inches, and in thickness from No. 10 gage and over down to No. 19 gage, and in length from two hundred feet and over down to twenty feet. Several trains of rolls are required for rolling metal strips of such various dimensions. These trains must vary greatly in their capacity as well as in their design and arrangement for rolling all the said widths, lengths, and gages of metal strips. As the average tonnage of certain sizes is, at times, comparatively small and a large number of grooved rolls for rolling strips of various sizes must always be employed and kept on hand, the production of finished material under ordinary practice becomes both costly and tedious, while the installation of a plant with the necessary mills suitable for rolling even the smaller part of the above named sizes must of necessity cover a large area of ground, as it has not heretofore been possible to place the necessary trains with their auxiliary machinery in one building of practicable and moderate dimensions. The management and maintenance of a plant in different buildings or at separate points, and the distribution of fuel and power in the same becomes a very serious matter and not easy of satisfactory economic solution.

The object of my invention is to roll all of the above-named sizes of strip metal in one building of moderate and entirely practicable dimensions with power distribution of the most compact and economic design.

Referring to the accompanying drawings, Figures 1 and 2 are a plan showing conventionally the general arrangement of the mills in a plant involving my invention, the figures being continuations of each other at the line *a--a*. Fig. 3 is a vertical longitudinal section through two pairs of rolls of a finishing train. Fig. 4 is a side elevation showing conventionally a finishing train of rolls with the mechanism for automatically transferring the metal strips from

one stand of rolls to the next. Fig. 5 is an end view of the gearing for driving the rolls. Fig. 6 is a view showing the relation of the several tables, guideways, and pushers for the finishing mills, the stands of rollers being shown closer together than the stands of rolls in Fig. 4, thereby causing the guideways *P* and *P'* to appear to have different lengths and inclinations on Fig. 6 than on Fig. 4.

The roughing trains *A* and *B* are driven by the engine or motor *C*, the main gearing *D* being placed about midway between the trains *A* and *B*. These trains may be of any suitable type. The train *A* is preferably of the universal type. The horizontal rolls, one marked *a*, being shown, should be of adequate length and proportionate diameter, and the vertical rolls *a'* should be suitably arranged and constructed for the rolling of slabs from twenty inches wide or over down to, say, six inches, and of any suitable thickness. The slabs are first heated in the furnaces *E* and placed on the approach table *F* in line with the tables *G* *G'* on either side of the train *A*. The slabs are repeatedly passed from the table *G* through the train *A* to the table *G'*, and from the latter through the train *A* back to the table *G* in the usual well known manner until the slabs have been reduced to the proper length and thickness, whereupon they are conveyed immediately to the table *H*, from which they are fed into the vertical edging mill *I* comprising a pair of rolls *i*, *i*.

J is the motor for driving the mill *I*.

The slabs, which, after having been passed through the roughing train *A*, are about one-half inch thick and of any width up to twenty inches or over, receive one pass in the edging mill *I* in order to roll them to exact final width and for the purpose of removing the scale therefrom.

The slabs pass from the mill *I* to the table *K* (Fig. 3), from which they are fed to first pair of rolls *l* of the finishing train *L*. The sheets issuing from the rolls *l* pass to the table *M*, and then along the curved guides *N*, *N'* and to the second pair of finishing rolls *l'*, which lie somewhat above them. The sheets pass from the rolls *l'* to the table *K'* which is above the table *K*. The pusher *O*, operated by fluid pressure from the cylinder *o* or otherwise pushes the sheets from the table *K'* laterally to the inclined slide-way *P*, down which they slide to the feed-

table Q in front of the rolls l^2 from which they pass along a curved guide and are turned back to the rolls l^3 . From the rolls l^3 the sheets pass to the table R from which 5 they are pushed by the pusher O' down the slideway P' to the table S in front of the third stand of finishing rolls l^4 composed of a single pair. The stand of rolls l^2 and l^3 together with their feed tables and curved 10 guides are duplicates of the stand of rolls l and l' with their feed tables and curved guides and need not be separately described or more fully shown. The finishing rolls are driven by the engine or motor C', D' 15 representing the main gearing.

In Fig. 6 I have shown conventionally means for operating the feed rollers for the tables. The rollers in the tables K, Q, and S are driven by bevel gearing k , q , and s , in 20 a well-known manner, and the rollers K' and R are driven from the shafts of the rollers K and Q by the spur-gearing k' and q' .

From the rolls l^4 the finished sheets pass 25 to the table T from which they are transferred to the transfer table and cooling bed T' whence they are moved to the shear table T² where they may be subjected to the action of the shears t and t' .

The curved guides N, N' (Fig. 3) comprise two pivoted member, one being pivoted at its lower edge and arranged to swing up and cover the lower portion of the space between the levels of the passes of the two 30 pairs of rolls l and l' , and the other being pivoted at its upper edge and arranged to swing downwardly and cover the upper portion of the said space. The lower portion of the member N' lies on the outer face of 35 the upper portion of the lower member N, so that the sheets cannot pass between the said members while being guided by them. The members N and N' are yieldingly held in the position shown in full lines by the 40 upper portion of the lower member N, so that the sheets cannot pass between the said members while being guided by them. The members N and N' are yieldingly held in the position shown in full lines by the 45 coiled expansion springs n which bear against the trunnion blocks n' and the respective members N and N', there being within the springs the rods n^2 pivoted to the said members and extending through 50 the trunnion blocks. When the sheets are fed through the lower rolls l faster than they are fed through the upper rolls l' the metal pressing against the members N, N', causes them to be swung out as shown in 55 dotted lines, the sheet being looped beyond the said members as shown by the dotted line n^3 . I have arranged the gearing for driving the rolls so that the upper pair of rolls will be driven faster than the lower 60 pair of rolls as shown on Fig. 5, which will now me explained.

The main gearing D' comprises the large spur-gear d driven directly by the shaft c of the motor C', and the two spur-gears d' 65, and d^2 of different sizes meshing with the

gear d , the gear d' being larger than the gear d^2 and connected to drive the rolls l , while the smaller gear d^2 is connected to drive the upper rolls l' . By this construction the motor may be driven at a safe speed 70 while the different pairs of rolls may be driven at high speeds of different rates. The gearing D² is the same as the gearing D'.

U is a feed table on which billets are conveyed to a position between the heating furnace E' and the pusher W, by which the billets are pushed into the furnace. The billets pass from the furnace to the table G² and then to the roughing train B, whose 80 rolls, commonly called box and edge rolls, are grooved in the usual manner, so that by passing the heated billets through them a sufficient number of times and rotating the billets ninety degrees between passes, the 85 billets will be formed into flats of the desired widths. From the roughing mill B the flats pass over the table G³, through the vertical edging mill I' having the rolls i' and the driving motor or engine J'. The 90 flats then pass over the table G⁴ and through the intermediate flattening mill V, and thence over the table G⁵ and through the edging mill I² having the vertical rolls i^2 and driving motor J². From the mill I² the 95 flats pass over the table K to the finishing mill L' which is constructed like the finishing mill L. The mill L' is accompanied by feed tables, curved guides, sheet pushers, slideways, and other auxiliary mechanism 100 like those which accompany the mill L, so that it is unnecessary to describe the same further. The same parts in the mills L and L' are indicated by the same reference characters. The rolls of the mill L' are driven 105 by the engine C², D² representing the main gearing. The rolls of the flattening mill are driven from the engine C² by the belt Y.

From the rolls l^4 of the finishing train L', the sheets pass to the table T⁴, whence they 110 are removed to the transfer and cooling bed T⁴ and then to the shear table T⁵, where they are sheared by the shears t^2 and t^3 .

When the finished sheets are very thin and the feed through the rolls l^4 in the 115 mill L' is required to be faster than that given to them by the engine C², they may be driven separately from the engine C' by means of the belt Y'.

With the exception of the manipulation 120 of the billets in the breaking-down mill B, the operations are carried on automatically from the furnace to the shear table.

The mills A, I, and L are made of such sizes and designs as to make strips or sheets 125 of all widths from twenty inches or over down to six inches, while the mills B, I', V, I², and L' are made of such sizes and designs as to make strips or sheets of all widths from eight inches down to one and 130

a half inches, the two sets of mills covering the entire range of widths of strips or sheets.

By arranging the two sets of mills side by side so that the roughing mills A and B can be driven by the same engine C; by arranging the five pairs of finishing rolls of the mills I₂ and I' in three stands in line with one another; and by arranging the shear tables T² and T' so that they are close to each other and without any obstructions between them, I economize greatly in the number of persons required to operate and superintend the operations and in the space required. The two sets of mills arranged and constructed substantially as herein described can be arranged in a building not exceeding eighty-five feet wide and four hundred feet long, making the supervision of the plant easy and the cost of the plant and of its operation very low. The distribution and location of the motor power is such that the piping or wiring is very short.

I claim--

1. In a finishing mill for sheet metal, a series of stands of rolls arranged side by side, each stand of rolls comprising a pair of upper and a pair of lower rolls except the last stand which comprises a single pair of rolls, a pair of yielding curved guides for each stand except the last for guiding the sheets from the lower to the upper pair of rolls, feed tables for feeding the sheets to the lower pairs of rolls and to the last pair

of rolls, tables for receiving the sheets from the upper pairs of rolls, guideways from the upper table in one stand to the table for the lower pair of rolls in the next stand and for the pair of rolls in the last stand, and means for moving the sheets from the upper tables to the guideways.

2. In a finishing mill for sheet metal, a plurality of stands of rolls arranged side by side and all but the last comprising two pairs of rolls one above the other and at the rear thereof, and means for pushing the sheets laterally and guiding the same from an upper pair of rolls to the next lower pair of rolls in the succeeding stand of rolls.

3. In a finishing mill for sheet metal, a plurality of stands of rolls arranged side by side and all but the last comprising two pairs of rolls one above the other and at the rear thereof, the lower pairs of rolls being in one alinement and the upper pairs of rolls in another alinement, and means for pushing the sheets laterally and guiding the same from an upper pair of rolls to the next lower pair of rolls in the succeeding stand of rolls.

Signed at Pittsburgh, Pa., this 25th day of June, A. D. 1913.

VICTOR CHARTENER.
